UNITED STATES PATENT OFFICE.

FRANCIS JENKINS OF WASHINGTON, DISTRICT OF COLUMBIA.

STARTING DEVICE FOR INTERNAL-COMBUSTION ENGINES.

1,024,077.

Specification of Letters Patent. Patented Apr. 23, 1912.

Application filed June 18, 1910. Serial No. 567,683.

To all whom it may concern:

Be it known that I, CHARLES FRANCIS JENKINS, citizen of the United States, residing at Washington, District of Columbia, ⁵ have invented certain new and useful Improvements in Starting Devices for Internal-Combustion Engines, of which the following is a specification.

This invention relates to that class of devices employed for starting internal-combustion engines, is primarily intended for automobiles, and has for its main object the employment of mechanisms which will permit the engine being started from the seat and without the danger and laborious effort of "turning-over" the engine, or the complicated devices employed when compressed air is used for the purpose.

Simply stated, the method employed herein is the manual charging of one or more of the engine cylinders with a combustible mixture which can readily be exploded by means of the ignition devices now on the engine, thus putting the engine into automatic action. Figure 1 is a top view of

In the drawings, Figure 1 is a top view of the pump and distributing mechanism; Fig. 2 a distributing valve; Fig. 3 another view of the same; Fig. 4 a sectional view of the relief valve, and Fig. 5 a diagrammatic view of the assembled device.

In all the figures like symbols refer to like parts, in which—

like parts, in which
1 is a carbureter, of any suitable type for
35 vaporizing gasolene and mixing it with air
to form an explosive compound; 2 the mani-
fold connecting the carbureter with the sev-
eral cylinders of the engine; 3 a pipe lead-
ing from the manifold, past the check-valve
40 4, to the pump, 5. From the pump a similar
pipe leads past the regulating-valve 6 to the
reservoir 7. This pipe has a branch 8 lead-
ing to the distributing-valve 9. From this
distributer pipes 10 lead one each to each of
45 the cylinders A, B, C, and D, through the
valves 11 which are controlled by the handle
12, located within reach of the driver.
Frame 13 supports both the distributer and
the pump. The rotor 14 of the valve 9 is
50 fixed on one end of the shaft 15 on the other
end of which the crankhead 16 is mounted.
In the base 17 of the pump 5 an inlet check-
valve is located, and also an exit valve 19.

The latter is provided with a hook 20 which loosely engages the loop 21 attached to the 55 plunger 22 above which is the spring 23.

The shaft 15 being rotatively attached to the engine crank-shaft by any suitable means which will keep it in time therewith, the pump will operate to charge the reservoir 7 with a properly-mixed gas drawn from the carbureter manifold. When the pressure in the reservoir has reached a predetermined point, say, twenty-five pounds, the plunger 22 raises holding the check-valve 19 off its seat, and this stops the effective operation of the pump and prevents a further increase in the pressure of the gas in the reservoir. The distributor 14 being also attached to the shaft 15 is rotated in time with the crank-shaft of the engine, and as the cut-away portion 14^a of the valve uncovers two of the pipes 10 leading to the cylinders, the gas has an open passage from the reservoir through the pipes 8, the valve-space 14^a, and the pipes 10, 10 to two of the cylinders when the hand-valves 11 are opened. The cylinders then quickly fill to a pressure equal to that in the reservoir and then the hand-valves are closed, by a turn of the handle 12. If now the charge above the piston which is in proper position is exploded by a touch of the sparking-button (with some form of which practically every automobile is now fitted) the piston is driven downward. This causes an explosion in the other cylinder, immediately following which the engine automatically takes up its regular cycle of operation.

Whether the piping 10 is arranged as shown in the drawings or in some other way is immaterial, the only essential being that the pipes leading to the two cylinders in which the inlet or the exhaust ports are open shall be closed by the valve 14.

What I claim, therefore, is—

The combination with a series of engine cylinders, of a carbureter, a reservoir, a pump drawing gas from the carbureter and forcing it into the reservoir, a valve 100 preventing return of the gas to the carbureter, a valve normally preventing the return of the gas from the reservoir to the pump, means whereby excess of pressure in the reservoir holds the last mentioned valve 105 open, a distributor casing in open commun-.

cation with said reservoir, conduits leading from the distributer to the cylinders, respectively, hand operated valves normally closing all said conduits, and a distributer valve

5 in said casing adapted to keep said reservoir at all times in communication with at least one of said conduits.

In testimony whereof I have affixed my signature in presence of two witnesses.

CHARLES FRANCIS JENKINS.
